UNITED STATES PATENT OFFICE

2,258,504

ROTARY FLUID PRESSURE ENGINE AND
THE LIKE

Melville Bertram Booth, Allesley, Coventry, England, assignor to The Keelavite Company, Limited, Coventry, Warwickshire, England, a company of Great Britain

Application May 27, 1938, Serial No. 210,503
In Great Britain June 4, 1937

13 Claims. (Cl. 103—125)

This invention relates to rotary fluid pressure motors, pumps and the like adapted to be operated by or to operate upon a fluid, whether gaseous or liquid, hereinafter termed the working fluid, and whether employed primarily to act on or be acted upon by the working fluid or employed as or incorporated in devices such as transmission devices or fluid meters.

For brevity such motors or pumps will herein-after be referred to as rotary engines.

The invention is concerned with rotary engines of the kind comprising an annular blade chamber, blades extending across the blade chamber so as to make a sealing fit with the inner and outer circumferential walls of the blade chamber relatively to which the blades rotate about the axis of the blade chamber, a rotary abutment extending across the blade chamber between inlet and outlet ports and having a circumferential surface which is circular in cross-sections at right angles to its axis of rotation and makes a sealing fit at all times with abutment recesses of part-circular cross-section respectively in the inner and outer circumferential walls of the blade chamber, one or more blade-receiving recesses being provided in the periphery of the abutment, each of which during rotation of the abutment comes into position to receive a blade and permit it to pass the abutment as the blade during its rotation comes to the part of the blade chamber across which the abutment extends.

The object of the invention is to provide a rotary engine of the above kind, the capacity of which can be varied.

To this end in a rotary engine of the kind referred to according to the present invention, the end walls of the blade chamber are axially movable relatively to one another and the blades pass and are axially slideable through slots in one end wall of the blade chamber, which end wall rotates with the blades while they are held from axial movement relatively to the other end wall but rotate relatively thereto.

For the sake of convenience the member carrying the blades will hereinafter be referred to as "the rotor."

The rotor is conveniently connected through a thrust bearing to the end wall relatively to which it rotates. Further, a fluid pressure chamber may be provided in which fluid pressure derived from the blade chamber acts to counterbalance partially or wholly the axial force exerted by fluid pressure in the blade chamber on the axially movable end wall. Preferably, in such an arrangement opposite end walls of the fluid pressure

chamber are respectively rigid with the end walls of the blade chamber so that the fluid pressure in the fluid pressure chamber counterbalances partially or wholly the axial forces tending to separate the end walls of the blade chamber without the interposition of thrust bearings.

In one arrangement according to the invention the abutment and the end wall which rotates with the blades are held from axial movement while the other end wall and the rotor are movable axially. In such an arrangement the end wall which rotates with the blades may be constituted by the end face of a cylindrical rotary member or flange having axial slots through which the blades pass and a chamber within it in which the rotor lies and in which this rotor can be moved axially to cause the desired axial movement of the blades through the slots in said flange. In this case the cylindrical rotary member may be connected to a piston disposed in a cylinder rigid with the axially movable end wall, the chamber on one side of the piston communicating with the blade chamber so that the fluid pressure derived from the blade chamber acts on the appropriate face of the piston and the adjacent end of the cylinder to counterbalance partially or wholly the axial forces exerted by the fluid pressure within the blade chamber on the two end walls thereof. Such a construction is particularly suitable for the case where the abutment is supported in bearings in a part rigid with the outer circumferential wall of the blade chamber and the rotary cylindrical member may be mounted on a driving shaft so that rotation is imparted to the rotor from the shaft through this rotary cylindrical member.

In an alternative arrangement the end wall which is held from axial movement relatively to the blades is stationary and the abutment is supported in a part which is movable axially with the abutment and the end wall which rotates with the blades relative to the rotor. Such an arrangement is particularly convenient when the abutment is supported in bearings in a part constituting the inner circumferential wall of the blade chamber. The end wall through which the blades pass may then be constituted by the end face of a cylindrical member which lies round one end portion of the part in which the abutment is supported and which is carried by a disc-like member while the blades are carried by a second disc-like member and extend therefrom through axial slots in the said cylindrical member.

The invention may be carried into practice in

various ways but two constructions according to the invention are illustrated diagrammatically by way of example in the accompanying drawings, in which:

Figure 1 is a sectional side elevation of one construction taken on the line 1—1 of Figure 2;

Figure 2 is a section on the line 2—2 of Figure 1;

Figure 3 is a section on the line 3—3 of Figure 1;

Figure 4 is a section on the line 4—4 of part of the construction shown in Figure 1;

Figure 5 is a section on the line 5—5 of Figure 1 with the parts in the position they occupy when the capacity of the engine is reduced;

Figure 6 is a similar view to Figure 1 of an alternative construction according to the invention;

Figure 7 is a section on the line 7—7 of Figure 6;

Figure 8 is a section on the line 8—8 of Figure 6; and

Figure 9 is a section on the line 9—9 of Figure 6 with the parts in the position they occupy when the capacity of the engine is reduced.

In the construction illustrated in Figures 1 to 5, the engine comprises a casing Q supporting bearings in which is a main shaft Q¹ connected by gearing Q² to a shaft Q³. Mounted on the shaft Q¹ is a disc-like part Q⁴ having an axially extending flange Q⁵ at the end of which is formed an internal flange Q⁶. The internal flange Q⁶ constitutes one end wall of an annular blade chamber R² and is provided with two slots as shown in Figures 1, 2 and 3 through which extend and can slide blades R formed on a rotor R¹ which thus rotates with the member Q⁴ but can slide axially relatively thereto. The outer wall of the blade chamber is constituted by a part of the casing Q while its inner wall and its other end wall are constituted by a member S mounted to slide but not to rotate within the casing Q and carrying bearings which support the rotor R¹.

Formed or mounted on the shaft Q³ is a rotary abutment S¹ which engages part-cylindrical abutment recesses R³, R⁴ respectively in the part of the casing Q constituting the outer wall of the annular blade chamber and in the part of the member S constituting the inner circumferential wall of the blade chamber as shown more particularly in Figures 2 and 5. Inlet and outlet ports T, T¹ are formed in the casing so as to communicate with the annular blade chamber respectively on the two sides of the rotary abutment S¹.

The rotary abutment S¹ is provided with two blade-receiving recesses S² and the arrangement is such that the abutment extends across the blade chamber at all times and one or other of the blade-receiving recesses comes into position when required to permit each blade to pass the abutment. A continuation of the abutment-receiving recess R⁴ in the member S extends to the left (in Fig. 1) of the blade chamber and a correspondingly formed part of a member Q⁷ constituting part of the casing extends into and makes a fluid-tight seal with this continuation.

The member S may on its low pressure side be formed with a cylinder S³ in which lies a piston Q⁸ on an extension of the shaft Q¹, the cylinder S³ communicating with the blade chamber so that the pressure therein counteracts partially or wholly the axial thrust on the flange Q⁶ constituting an end wall of the blade chamber and also similarly counteracts the axial thrust on the

other end wall which is constituted by the member S without the interposition of thrust bearings.

Figure 1 shows the parts in the position of maximum capacity. When the capacity is to be reduced the member S and with it the member R¹ carrying the blades are moved to the right. It will then be seen that the axial distance between the end wall of the blade chamber formed by the member S and the end wall formed by the flange Q⁶ is reduced, the effective length of the blades R being correspondingly reduced by withdrawal of these blades through the slots in the flange Q⁶ so that the axial length of the blade chamber and hence the capacity of the engine is reduced.

In order to prevent leakage occurring from the righthand end of the abutment recess R⁴ in the member S as each blade-receiving recess S² passes over it when operating on reduced capacity, the flange Q⁵ is formed on its interior on each side of each of the slots in the flange Q⁶ with walls Q⁹ which make a fluid-tight seal with the adjacent part of the circumference of the member S at such times as the abutment-receiving recess R⁴ is brought into communication with the inlet or outlet port by a blade-receiving recess S² in the abutment.

In the construction illustrated in Figures 6 to 9, the engine is also of the variable capacity type and comprises a casting T² supporting in bearings a main shaft U carrying a rotor U¹ provided with projections U² which constitute blades lying within an annular blade chamber V the outer circumferential wall of which is formed by a part of the casting T² while its inner circumferential wall is formed by a member W mounted to slide but not to rotate within the casting T².

Mounted on a shaft V¹ within the casing is a disc V² formed with a flange V³ at its circumference which is slotted at diametrically opposite points to permit the blade projections U², U³ to slide through it. The left-hand end face of the flange V³ constitutes the right-hand end wall of the annular blade chamber while the left-hand end wall of this blade chamber is constituted by a shoulder T³ on the casing.

The shaft V¹ is supported in bearings in the member W and also in a bearing in the end of the shaft U and is adapted to slide axially with the member W relatively to the casing, the shaft U and the parts rigidly connected thereto being capable of rotation but not of axial movement in the casing.

Mounted in bearings in the member W and connected to the shaft V¹ by gearing so as to rotate in the same direction as this shaft is a rotary abutment X having a single blade-receiving recess X¹ therein, this abutment engaging at all times abutment recesses Y, Y¹ respectively in the member W and in the casing and lying between inlet and outlet ports X², X³.

Formed in the casing T² is a cylinder T⁴ in which lies a piston V⁴ mounted on the shaft V¹, the cylinder T⁴ being connected to the working chamber so that the pressure in this cylinder by acting on the right hand face (Fig. 6) of the piston V⁴ counterbalances the pressure acting on the end wall of the blade chamber constituted by the member V³.

In Figure 6 the parts are shown in the position of maximum capacity. When, however, it is desired to reduce the capacity of the engine, the shaft V¹ and the member W are moved to the left so that the end wall of the blade chamber

constituted by the member V^3 approaches the end wall T^1 so as to reduce the axial length and hence the capacity of the blade chamber. It will be understood that a part of the member W engages and moves to the left within an extension of the abutment-receiving recess Y^1 so that the abutment is free to move to the left with the member W .

In order to prevent leakage through the part of the abutment recess Y^1 vacated by the abutment when operating with reduced capacity, the parts of the casing adjacent to the edges of this recess are formed as shown at T^6 in Figures 7 and 9 and it will be seen from Figure 9 that the seal between the inlet and outlet ports is thus maintained by the cooperation between the parts T^6 , the member V^3 and the blades U^3 in the part of the blade chamber vacated by the abutment.

It is to be understood that the constructions diagrammatically illustrated in the drawings are given purely by way of example and that the form of the engine may vary within wide limits within the scope of the appended claims.

What I claim as my invention and desire to secure by Letters Patents is:

1. In a rotary engine comprising an annular blade chamber one end wall of which is slidable axially relatively to the other end wall, and one end wall of which is rotatable, a rotor carrying blades which extend through slots in said rotatable end wall so as to be slidable through such slots when relative axial movement between the end walls takes place, the blades making a sealing fit with the two end walls and with the inner and outer circumferential walls of the blade chamber relatively to which circumferential walls the rotor and blades rotate about the axis of the blade chamber, inlet and outlet ports connecting with said blade chamber, at least one rotary abutment arranged to rotate about an axis parallel to but displaced from that of the blade chamber, the abutment extending across the blade chamber between said inlet and outlet ports and having a circumferential surface which is part-circular in cross-sections at right angles to its axis of rotation, abutment recesses of part-circular cross-section respectively in the circumferential walls of the blade chamber and with which recesses said abutment makes a sealing fit at all times, and at least one blade-receiving recess in the abutment which during rotation of the abutment comes into position to receive a blade and permit it to pass the abutment as the blade, during its rotation with the rotor, comes to the part of the blade chamber across which the abutment extends.

2. A rotary engine having the combination of features set forth in claim 1 and a piston and cylinder structure one element of which is rigid with the axially movable end wall while the other is rigid with the fixed end wall, the chamber enclosed by the piston and cylinder structure being subject to the pressure in the blade chamber so as to counterbalance at least partially the axial force exerted by the pressure within the blade chamber on the axially movable end wall.

3. A rotary engine comprising an annular blade chamber one end wall of which is axially movable and one end wall of which is rotatable relatively to the other end wall, a rotor arranged to rotate about the axis of the blade chamber and carrying blades which extend through slots in and rotate with the rotatable end wall relatively to the inner and outer circumferential

walls of the blade chamber and can slide through such slots while being held from axial movement relatively to the other end wall when relative axial movement between the end walls takes place, the blades making a sealing fit with the two end walls and with the inner and outer circumferential walls of the blade chamber, at least one rotary abutment arranged to rotate about an axis parallel to but displaced from that of the blade chamber and held from axial movement relatively to the end wall which rotates with the blades but being axially movable relative to the other end wall, the abutment extending across the blade chamber between inlet and outlet ports and having a circumferential surface which is part-circular in cross-sections at right angles to its axis of rotation, abutment recesses of part-circular cross-section respectively in the inner and outer circumferential walls of the blade chamber with which recess said abutment makes a sealing fit at all times, and at least one blade-receiving recess in the abutment which, during rotation of the abutment, comes into position to receive a blade and permit it to pass the abutment as the blade, during its rotation with the rotor, comes to the part of the blade chamber across which the abutment extends.

4. A rotary engine comprising an annular blade chamber having one rotatable and one non-rotatable end wall, one end wall being axially movable while the other is held from axial movement while both circumferential walls are held from rotation with one held from axial movement relatively to one end wall and the other held from axial movement relatively to the other end wall, a rotor arranged to rotate about the axis of the blade chamber and carrying blades which extend through slots in the rotatable end wall and are held from axial movement relatively to the non-rotatable end wall, the blades making a sealing fit with the end walls and the inner and outer circumferential walls of the blade chamber, at least one rotary abutment mounted in bearings in that circumferential wall which is held from axial movement relatively to the rotating end wall and so that the abutment is rotatable about an axis parallel to but displaced from that of the blade chamber, the abutment extending across the blade chamber between inlet and outlet ports and having a circumferential surface which is part-circular in cross-sections at right angles to its axis of rotation and makes a sealing fit at all times with abutment recesses of particular cross-section respectively in the inner and outer circumferential walls of the blade chamber, and at least one blade-receiving recess in the abutment which, during rotation of the abutment, comes into position to receive a blade and permit it to pass the abutment as the blade, during its rotation with the rotor, comes to the part of the blade chamber across which the abutment extends.

5. A rotary engine comprising an annular blade chamber having a stationary outer circumferential wall and an inner circumferential wall which is rigid with one end wall and is held from rotation but is capable of sliding axially, the other end wall which is mounted to rotate about the axis of the blade chamber being held from axial movement, a rotor arranged to rotate about the axis of the blade chamber and carrying blades which extend through slots in the rotatable end wall and are axially movable with the non-rotatable end wall, the blades making a sealing fit with the two end walls and the circumferential walls

of the blade chamber, at least one rotary abutment mounted in bearings in the outer circumferential wall of the blade chamber so as to be held from axial movement therein while rotating about an axis parallel to that of the blade chamber, the abutment extending across the blade chamber between inlet and outlet ports and having a circumferential surface which is part-circular in cross-sections at right angles to its axis of rotation and makes a sealing fit at all times with abutment recesses of part-circular cross-section respectively in the outer and inner circumferential walls of the blade chamber, and at least one blade-receiving recess in the abutment which, during rotation of the abutment, comes into position to receive a blade and permit it to pass the abutment as the blade, during its rotation with the rotor, comes to the part of the blade chamber across which the abutment extends.

6. A rotary engine comprising an annular blade chamber the outer circumferential wall and one end wall of which are stationary while the inner circumferential wall while being held from rotation is axially movable relatively to the casing together with the other end wall which is rotatable about the axis of the blade chamber, a rotor arranged to rotate about the axis of the blade chamber and held from axial movement relatively to the stationary circumferential wall, blades carried by said rotor and extending through slots in the rotatable end wall, the blades making a sealing fit with the two end walls and the two circumferential walls of the blade chamber, at least one rotary abutment mounted in bearings in the inner circumferential wall of the blade chamber so as to be held from axial movement relatively thereto but to be rotatable about an axis parallel to but displaced from that of the blade chamber, the abutment extending across the blade chamber between inlet and outlet ports and having a circumferential surface which is part-circular in cross-sections at right angles to its axis of rotation and makes a sealing fit at all times with abutment recesses of part-circular cross-section respectively in the two circumferential walls of the blade chamber, and at least one blade-receiving recess in the abutment which, during rotation of the abutment, comes into position to receive a blade and permit it to pass the abutment as the blade, during its rotation with the rotor, comes to the part of the blade chamber across which the abutment extends.

7. A rotary engine comprising the combination of features set forth in claim 3 and a piston and cylinder structure one element of which is rigid with the axially movable end wall while the other is rigid with the other end wall, the chamber enclosed by the piston and cylinder structure being subject to the pressure in the blade chamber so as to counter-balance at least partially the axial force exerted by the pressure within the blade chamber on the axially movable wall.

8. A rotary engine comprising the combination of features set forth in claim 5 and a piston and cylinder structure one element of which is rigid with the axially movable end wall while the other is rigid with the fixed end wall, the chamber enclosed by the piston and cylinder structure being subject to the pressure in the blade chamber so as to counter-balance at least partially the axial

force exerted by the pressure within the blade chamber on the axially movable end wall.

9. A rotary engine comprising the combination of features set forth in claim 6 and a piston and cylinder structure one element of which is rigid with the axially movable end wall while the other is rigid with the stationary end wall, the chamber enclosed by the piston and cylinder structure being subject to the pressure in the blade chamber so as to counter-balance at least partially the axial force exerted by the pressure within the blade chamber on the axially movable end wall.
